UNITED STATES PATENT OFFICE.

MARSHALL E. YADON, OF NEW YORK, N. Y., ASSIGNOR TO THE MOORE PRESS, INC.,
OF NEW YORK, N. Y., A CORPORATION OF NEW YORK.

DESIGN FOR A CATALOG COVER.

Application filed February 27, 1929. Serial No. 30,236. Term of patent 7 years.

To all whom it may concern:

Be it known that I, MARSHALL E. YADON, a citizen of the United States, and a resident of the city of New York, in the county of New York and State of New York, have invented the new, original, and ornamental Design for Catalog Covers, of which the following is a specification.

Reference is had to the accompanying drawing, forming part thereof, wherein

I claim:

The ornamental design for a catalog cover substantially as shown.

Signed at 461 8th Ave., in the county of New York and State of New York, this 21st day of February A. D. 1929.

MARSHALL E. YADON.
